UNITED STATES PATENT OFFICE.

OSCAR D. McCLELLAN, OF PHILADELPHIA, PENNSYLVANIA, ASSIGNOR, BY MESNE ASSIGNMENTS, TO THE SANITARY AND FERTILIZER COMPANY OF THE UNITED STATES, OF SAME PLACE.

FEULENT-MATTER RECEIVER.

SPECIFICATION forming part of Letters Patent No. 401,709, dated April 16, 1889.

Application filed December 26, 1888. Serial No. 294,713. (No model.)

To all whom it may concern:

Be it known that I, OSCAR D. McCLELLAN, a citizen of the United States, residing at Philadelphia, in the county of Philadelphia and State of Pennsylvania, have invented certain new and useful Improvements in Feulent-Matter Receivers, of which the following is a specification.

My invention has relation to that form of feculent-matter receivers shown, described, and claimed in another application for United States Letters Patent filed by me on the 14th day of November, 1888, Serial No. 290,778; and it has for its objects simplicity of construction and arrangement of parts, the nature or kind of compounds used for deodorizing and preventing the escape of the volatile salts contained in the liquid and solid matters and for decomposing their organic ingredients, the use of precipitants for precipitating or concentrating the organic matter in the liquids before and as they are filtered, and an arrangement of filtering-beds to subject the liquids to the action of the filtering material for an increased length of time, whereby the results to be derived from the employment of the receivers are obtained in a more thorough and efficient manner, and the same are made more commercially available for use.

My invention accordingly consists of the combinations, constructions, and arrangements of parts, as more particularly described in the specification and pointed out in the claims, reference being had to the accompanying drawings, wherein—

Figure 1 is a side elevation of a feculent-matter receiver embodying my improvements. Fig. 2 is a front end elevation. Fig. 3 is a longitudinal section, partly in elevation; and Fig. 4 is a detail section on line 1 1, Fig. 3.

A represents the outside box or casing of the receiver, having a top, a , provided with a seat-opening, a' , a transversely-located slot or passage-way, a^2 , back of the seat-opening, and a seat-lid, a^3 , hinged to top a , as indicated at a^4 .

Within casing A is a sheet-metal or other suitable box or casing, B, suitably constructed, so as to be preferably non-oxidizable, and

above the bottom of which are located horizontally-arranged partitions $C C' C^2$, of which any desired number may be used, and are preferably reversely inclined to one another, as indicated more plainly in Fig. 3, to provide a number of lower chambers, $D D' D^2$, of comparatively narrow depth, and a large upper chamber contiguous to the seat-opening a' .

The partitions C , C' , and C^2 may be held in position within casing B in any suitable manner; but to provide an economical support therefor, so that they can readily be removed from casing B, I have shown said partitions having depending side flanges, c , (see more plainly Fig. 4,) the flanges c of the lowest partition, C^2 , resting on the bottom b of casing B, and the flanges of the each succeeding partitions above resting on the partition below the same. The large upper chamber is divided by a removable transverse partition, E, into front and rear chambers, D^3 and D^4 , respectively. The chamber D^3 has at its front end a vertically-inclined perforated or wire partition, E' , to further divide said chamber and provide a smaller chamber, D^5 , in front of the same.

In partition C, at any suitable part thereof serving as the floor or bottom for chamber D^4 , is a depending pocket or box, G, having perforated sides and bottom and a perforated removable cap or cover, g , and for chamber D^5 a corresponding pocket, G' , is made in partition C. The partitions C' and C^2 , at their lower parts and at opposite ends, are also provided with corresponding pockets, G^2 G^3 , so that communication from chamber D^4 is by way of pocket G to chamber D^2 , thence by way of pocket G^2 in partition C' to chamber D' , and by way of pocket G^3 in partition C^2 to chamber D. The chambers D^3 and D^5 have a corresponding communication by way of pocket G' and chambers $D^2 D'$ and pockets $G^2 G^3$, respectively, with chamber D. The chamber D is the outlet-chamber, and may be provided with a stop-cock, f , as indicated in full lines, Figs. 1 and 3; or said cock may connect with a service-pipe, as indicated in dotted lines y , Fig. 1, for connection with a sewer or other drain, as fully described in said named application. In the pockets G G' G^2

G³ is placed alum or other suitable material or compound having precipitant properties, and in chambers D' and D² is placed pulverized slag, coke, coal-dust, sawdust, or equivalent materials, either single or suitably combined, and these chambers D' D² are the filtering-chambers for the urine or liquid feculent matter.

The rear of the casing A, or, if desired, any other suitable side or end of the same, is composed of a hinged side or end, a⁵, for the purpose of admitting of easy insertion of the casing B and its contents into casing A, and for removal therefrom, for purposes set forth in said above-named application, a suitable opening, a⁶, being provided in said door end or side a⁵ for the cock f or its pipe-connection with chamber D.

At the rear end of the casing A, above the same and inclosing the slot or passage-way a², is a receptacle or magazine, H, having a hinged or removable lid, h, an inclined bottom, h', which extends through slot or passage-way a² into the rear part of chamber D³.

The magazine H is divided by a curved or other suitably-configured partition, h², into upper and lower chambers, h³ h⁴, respectively. The partition h² does not extend to the incline h', there being a space or passage-way, h⁵, between said partition and incline, to permit communication between chambers h³ h⁴. The chamber h³ is filled with a supply of deodorizing, absorbing, and organic decomposing compound, as hereinafter described, and in chamber h⁴ are located the devices for ejecting charges of said compound into chamber D³ upon the human dejecta or feculent matter deposited therein, said chamber h⁴ communicating, by way of slot or passage-way a², with chamber D³.

The ejecting devices consist of a semicircular or segmental shaped and transversely located receptacle, charging-chamber, or valve, I, which extends across the chamber h⁴ the length of the opening or passage-way a² at the bottom of said chamber. Said valve I is pivoted at i to the sides of the magazine or receptacle H in any suitable manner, so that when tilted in either of the positions shown in full and dotted lines, Fig. 3, one or the other of its edges, i' i², contact with the incline h' of receptacle H. At the edge i' of valve I is an outward-curved flange, i³, conforming to the curve of the partition h² and serving as a gate to close opening h⁵ when the valve I is in position indicated in full lines, Fig. 3. At the opposite side of the valve I, and at or near its center, is a wide recess, i⁴, for the reception of a pin or lug, a⁷, on a bracket, a⁸, attached to the seat-lid a³, so that when the latter is raised or lowered the lug or pin a⁷ is moved through recess i⁴ on valve I, to respectively strike against either the sides i⁵ or i⁶ of said recess i⁴ to tilt the valve I in either of the positions indicated by dotted or full lines in Fig. 3, to admit of a charge of the compound in valve h³ entering the valve I and being ejected into

chamber D³, as hereinafter more fully set forth.

The compound placed in chamber h³ of receptacle H consists of suitable proportions of sulphate of magnesia, sulphate of lime, and slag or coke, coal-dust, or equivalent material. One proportion which I have found to be suitable is one-half pound of sulphate of lime, 75 one-half pound of sulphate of magnesia, and twenty-four pounds of the pulverized slag, coke, or coal-dust.

On each side of the receptacle H, and attached thereto, or otherwise suitably located, 80 are receptacles K K', having, preferably, inclined faces k, of the form usually employed for urinals, and are provided with hinged caps or covers k', and have an outlet-pipe, k², leading into chamber D⁴ of the receiver A. 85

A receiver, A, so made and attached to a drain-pipe, or separated therefrom, as desired, is used as follows: A suitable charge of the compound being inserted in chambers D² D', and a charge of alum or other suitable 90 precipitant being placed in the pockets G G' G² G³ in partitions C C' C², and a charge of compound placed in chamber h³ of receptacle H, and the seat-lid a³ being closed or down, the edge i² of valve I is away from and its edge i' is in contact with the incline h' of receptacle H, as indicated in full lines, Fig. 3, and communication is closed between chamber h³ and valve I in receptacle H, so that no part or charge of the compound in said chamber h³ can pass through opening h⁵ into valve I. As soon as the seat-lid a³ is raised for use the act of raising the lid and when almost raised causes the lug or pin a⁷ on bracket a⁸, secured to the lid, to strike the side i⁵ of the recess i⁴ in chamber I, to tilt or move the latter to the position indicated by dotted lines, Fig. 3, so that its edge i² contacts with the incline h' and its edge i' is away from the same, opening communication between valve I and chamber h³ of receptacle H, to admit of a charge of the compound in chamber h³ passing by gravity into valve I, which charge is held in the latter by reason of its edge i² contacting with the incline h'. After using the receiver and the human dejecta is deposited in chamber D³, the seat-lid is lowered, and when nearly closed the lug a⁷ on bracket a⁸ on lid a³ strikes the side i⁶ of the recess i⁴ in valve I to reversely tilt or move it to the position indicated in full lines, Fig. 3, as above described, closing communication between chamber h³ and valve I and opening the latter to chamber D³ in the receiver. The charge in valve I then passes down the incline h' 125 through slot or passage-way a² and distributes itself over and falls upon the dejecta in chamber D³, to deodorize and absorb the odors therefrom, and also to absorb and decompose the volatile salts and the organic matter contained 130 in the solids of the dejecta, as well as a portion of the volatile salts in the liquids accompanying the same. Any liquid portions of the latter or urinal matter deposited in

135

chamber D³ passes out of the latter through the perforated partition E' into chamber D⁵, and thence to the pocket G', containing the alum or precipitant material. The acid and other constituents of the alum combine with the soluble salts of sulphates and chlorides of the liquids as well as the other ingredients thereof to make them insoluble, and thus concentrate or precipitate the organic or coloring matter in said liquids, so that as the liquid with such matter travels through the inclined chamber D² such organic or coloring matter is more readily absorbed by the filtering compound in said chamber. After passing or filtering through the latter, it passes into the succeeding alum-pocket G² in partition C', to have any remaining organic matter further concentrated or precipitated to be more readily absorbed by the filtering compound in chamber D', through which said liquid passes to the succeeding alum-pocket G³, for further precipitation or concentration as it emerges into the outlet-chamber D.

If desired, a layer of alum or like material may be placed upon the bottom of the chamber D, for purposes above described, so that the liquid in chamber D, when ready to be drawn off therefrom or allowed to escape to the drain-pipe, is pure or inodorous and inorganic. The liquid matter deposited in chamber D³ is therefore separated from the solids therein and finds its way from chamber D⁵ through the successive filtering-chambers and alum-pockets, and to facilitate the passage of such liquid through the filtering-chambers, as well as to provide a large area or body of filtering medium for effectually accomplishing such filtration, the chambers D² D' or their partitions C C' C² are reversely inclined.

One of the receptacles K K' is employed to pass into chamber D⁴ the accumulations of urinal in households over night or otherwise, or for urinal purposes, so that the same will not come in contact with the solids in chamber D³, and the other is preferably used for wash-slops or like liquids which are usually thrown into slop-jars and emptied into the water-closets, both of which liquids pass from the receptacles K K' into the chamber D⁴, and from thence through the pocket G to the filtering-chambers and succeeding pockets G² G³, as above described for the liquid matter separated from the solids in chamber D³. If desired, instead of chamber D⁴ being one apartment, it may be divided into two, and each having a common astringent-containing pocket or a separate one, as indicated in dotted lines x x', Fig. 4. Again, while I have described the use of suitable ingredients for the compound in the chamber h³ of receptacle H, I do not limit myself thereto, as I can use the sulphate of magnesia and lime combined or separately, or I can use the pulverized slag, coke, &c., alone, the chemical action of the same being that when the sulphates come into contact with the ammonia of the solid or liquid secretions they combine and form non-

volatile compounds, the ammonia taking the sulphuric acid from the lime and magnesia to form sulphate of ammonia, which is non-volatile, and does not, therefore, escape from the receiver.

The slag, coke, coal-dust, or equivalent material have an absorbing and deodorizing property, as they are extremely porous and of themselves form a valuable fertilizer, the value of which for such purpose is materially enhanced when combined with human excrement, as above set forth.

As it is evident that the novel features of the foregoing-described device may be variously constructed and arranged without departing from the spirit of my invention, I do not limit myself to the same as shown and described. Thus, for instance, the casing A may be dispensed with and the top a, with seat-opening a' and fixtures thereon, may be used in connection with the casing B only, and, if desired, only one of the receptacles K K' need be used, especially when the chamber D⁴ is not divided into two compartments by the partition x', Fig. 4.

What I claim is—

1. A feculent-matter receiver having perforated deposit-chamber D³, in combination with a series of reversely-inclined filtering-chambers having perforations at the lower or terminal parts of their inclinations, substantially as set forth.

2. A feculent-matter receiver having deposit-chamber D³, having a perforated front side, E', a chamber, D⁵, in front of chamber D³, in combination with a series of filtering-chambers, substantially as set forth.

3. The receiver B, having perforated deposit-chamber D³, in combination with a series of reversely-inclined filtering-chambers, each having a perforated pocket at their exit or terminal end, and an outlet-chamber below the filtering-chambers, substantially as set forth.

4. A feculent-matter receiver having deposit-chamber D³, provided with a perforated side, E', and a chamber, D⁵, in front of side E', in combination with a series of filtering-chambers and an outlet-chamber below said filtering-chambers, substantially as set forth.

5. A feculent-matter receiver having deposit-chamber D³, in combination with a series of filtering-chambers and precipitant pockets or receptacles located in said filtering-chambers, substantially as set forth.

6. A feculent-matter receiver having separate deposit-chambers, located one in front of the other, a series of reversely-inclined filtering-chambers located below said deposit-chambers, and an outlet therefor, substantially as set forth.

7. In a feculent-matter receiver, the combination of separate chambers D³ D⁴, the pockets G G', filtering-chambers D² D', having pockets G² G³, and an outlet for said filtering-chambers, substantially as set forth.

8. The combination of chambers D³ D⁴, in-

tervening partition, E, inclined partitions C, C', and C², having pockets G G' G² G³, and outlet for the chambers bounded by said partitions C C' C², substantially as set forth.

5 9. The combination of chambers D³ D⁴ D⁵, reversely-inclined partitions C C' C², having pockets G G' G² G³, and chamber D, substantially as set forth.

10. In a feculent-matter receiver, the perforated pockets G G', containing alum, and chambers D² D', located one above the other, containing a charge of pulverized coke or equivalent material, and having perforated pockets G² G³, substantially as set forth.

15 11. In combination with perforated chamber D³, the chambers D² D', containing a filtering compound, perforated pockets G² G³ in said chambers D² D', a supply of alum in said pockets G² G³, and an outlet-chamber, D, substantially as set forth.

20 12. In combination with perforated chamber D³, the chambers D² D', containing a filtering compound, perforated pockets G² G³ in said chambers D² D', an outlet-chamber, D, a supply of alum in said pockets G² G³, and chamber D, substantially as set forth.

25 13. In combination with perforated chamber D³, the reversely-inclined partitions C C' C², having perforated pockets G' G² G³, and side flanges, c, substantially as set forth.

30 14. In combination with receiver-casing A, having seat-opening a', lid a³, and passage-way a² back of said seat-opening, of receptacle H, having incline h', extending through the passage-way a², valve I, pivoted within receptacle H near the bottom of incline h', and having two oppositely-located seating-edges facing and having alternate contact with incline h', and mechanism interposed between

35 seat-lid a³ and valve I for effecting the alternate contact of the valve-seating edges with said incline as the seat is raised and lowered, substantially as set forth.

40 15. In combination with receiver-casing A,

having seat-opening a', lid a³, and passage-way a² back of said seat-opening, of receptacle H, having incline h', extending through passage-way a² and divided into communicating chambers h³ h⁴, valve I, pivoted within chamber h⁴ near the bottom of incline h', and having two oppositely-located seating-edges for alternate contact with incline h', and a recess, i⁴, having ends i⁵ and i⁶, and bracket a⁸ on seat-lid a³, having pin a⁷ for alternate contact with ends i⁵ i⁶ as the seat is raised and lowered, substantially as set forth.

45 16. In combination with the receiver A, of a perforated deposit-chamber, D³, a separate chamber, D⁴, back of chamber D³ and having perforated pocket G', a receptacle, H, located 50 above chamber D⁴, separate receptacles K K', secured to receptacle H and having outlet-pipes leading into chamber D⁴, and a series of filtering-chambers located below chambers D³ D⁴, substantially as set forth.

55 17. In combination with a receiver, A, having seat-lid a³, a perforated deposit-chamber, D³, a chamber, D⁴, back of chamber D³ and having perforated outlet-pocket G', one or more separate receptacles, K K', communicating with chamber D³, and a series of filtering-chambers below chambers D³ D⁴, substantially as and for the purpose set forth.

60 18. In a receiver, A, having a seat-lid, a³, the combination of a deposit-chamber, a series of filtering-chambers, a separate chamber back of said deposit-chamber, a supply-receptacle, H, containing an absorbing compound and having charging devices actuated by said seat-lid to eject a charge of said compound 65 into said deposit-chamber, substantially as set forth.

In testimony whereof I affix my signature in presence of two witnesses.

OSCAR D. McCLELLAN.
